[57] CLAIM

The ornamental design for a package wrapping accessories caddy, as shown and described.

DESCRIPTION

FIG. 1 is a front elevational view of a package wrapping accessories caddy showing my new design;
FIG. 2 is a rear elevational view thereof;
FIG. 3 is a top plan view thereof;
FIG. 4 is a bottom plan view thereof; and,
FIG. 5 is a side elevation view thereof, both side views being essentially identical.

FIG. -1

FIG.-2

FIG. - 3

FIG. - 4

FIG. - 5
